UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A TUMBLER.

46,296.

Specification for Design.

Patented Aug. 18, 1914.

Application filed August 6, 1913. Serial No. 783,417. Term of patent 14 years.

To all whom it may concern:

Be it known that I, ANDREW JOHN SANFORD, a citizen of the United States, residing at Newark, Ohio, have invented a new, original, and ornamental Design for Tumblers, of which the following is a specification, reference being had to the accompanying drawing, forming part thereof.

Figure 1 is a side elevation of a tumbler showing my design, and Fig. 2 is a bottom plan thereof.

The sides of the tumbler are provided with flutes extending from the bottom toward the top, said flutes terminating below

the top so that a plain band is left of substantial depth. The tops of the flutes are "square" or practically straight, the ends of the top portions, however, being rounded to meet the ridges dividing the flutes from each other.

I claim:

The ornamental design for a tumbler, as shown and described.

ANDREW J. SANFORD.

Witnesses:

MAUDE BOTT,
I. M. PHILLIPS.
